Primary Examiner — Rachel A. Voorhies**CLAIM**

The ornamental design for a vehicle front lower bumper cover, as shown and described.

DESCRIPTION

FIG. 1 is a front elevational view of a vehicle front lower bumper cover, showing our new design;

FIG. 2 is a left side elevational view, thereof;

FIG. 3 is a right side elevational view, thereof;

FIG. 4 is a top plan view, thereof;

FIG. 5 is a bottom plan view, thereof.

FIG. 6 is a bottom, front, and left side perspective view, thereof; and,

FIG. 7 is a top, front, and left side perspective view, thereof. Any broken lines represent boundaries of the design and the areas within the broken lines shown in de-emphasized and half-tone rendering form no part of the claimed design.
